US00D839898S

(12) **United States Design Patent** (10) Patent No.: **US D839,898 S**
Zhong et al. (45) Date of Patent: ** Feb. 5, 2019

(54) **DISPLAY SCREEN OR PORTION THEREOF WITH GRAPHICAL USER INTERFACE**

G06F 3/0486; G06F 3/0488; G06F 3/04886; G06F 9/4443; G06F 17/211; G06F 17/212;

(71) Applicant: **SZ DJI Technology Co., Ltd.**, Shenzhen (CN)

(Continued)

(72) Inventors: **Heli Zhong**, Shenzhen (CN); **Shunnian Li**, Shenzhen (CN); **Xiaojun Li**, Shenzhen (CN)

(30) **Foreign Application Priority Data**

(57) **CLAIM**

The ornamental design for a display screen or portion thereof with graphical user interface, as shown and described.

Oct. 27, 2014 (CN) 2014 3 0411737
Oct. 27, 2014 (CN) 2014 3 0411830
Oct. 27, 2014 (CN) 2014 3 0411832
Oct. 27, 2014 (CN) 2014 3 0411938
Dec. 9, 2014 (CN) 2014 3 0512206
Dec. 10, 2014 (CN) 2014 3 0514206

DESCRIPTION

(51) **LOC (11) Cl.** **14-04**
(52) **U.S. Cl.**

USPC **D14/486**

(58) **Field of Classification Search**

USPC D14/485-495; D20/11; D21/324, 325
CPC G06F 3/048; G06F 3/0481; G06F 3/04817;
G06F 3/0482; G06F 3/0483; G06F
3/04842; G06F 3/0485; G06F 3/04855;

The FIGURE is a front view of a display screen or portion thereof with graphical user interface showing the claimed design.

The dashed broken lines around the FIGURE show a display screen or portion thereof, and form no part of the claimed design.

The dot-dash broken lines in the FIGURE and the areas within the dot-dash lines show portions of the graphical user

(Continued)

interface that form no part of the claimed design. The areas inside the dot-dot-dash broken lines do form part of the claimed design.

1 Claim, 1 Drawing Sheet
